REFRIGERATING APPARATUS

Carl A. Stickel, Dayton, Ohio, assignor to General
Motors Corporation, Dayton, Ohio, a corpora-
tion of Delaware

Application June 27, 1934, Serial No. 732,682

9 Claims. (Cl. 62—108.5)

My invention relates to refrigeration and more particularly to a device for facilitating the removal of an ice cube forming tray from a cooling element of a mechanical refrigerator.

It is well known that considerable difficulty is encountered in loosing and removing ice cube trays from the cooling or freezing element of household mechanical refrigerators. This inconvenience is caused by the formation of ice between the trays and their support in or on the freezing unit or evaporator causing the trays to firmly adhere or be bonded to the evaporator. Heretofore it has been the common practice to loosen the trays by inserting a pointed kitchen utensil, such as a knife or the like, between the tray and its support on the cooling element and pry the tray from the support. Such practice damages the trays, the tray supports and the freezing unit and is often ineffective and ultimately requires the use of heat to loosen the trays. I am aware that other means, such as cam and lever devices, built into the cooling element or incorporated as a part of an ice tray have been proposed for loosening the trays but these devices have not been entirely satisfactory because they become bonded or frozen tight and are sometimes very difficult to actuate. Moreover these devices have been constructed to be actuated only in a single direction for prying the tray loose from its support and it quite frequently happens that they become inoperative in the single direction, but if constructed so as to be actuated in a plurality of directions in accordance with the teaching of the present invention they would be rendered operative at all times because there is little likelihood of them being bonded or frozen tight against movement in more than one direction.

It is therefore an object of my invention to provide an improved device which can be easily manipulated to loosen and remove an ice cube tray from its support in or on a cooling element of a refrigerator without injury to either the element, the ice tray or its support.

Another object of my invention is to provide a device of this character which can be incorporated in a cooling element of a mechanical refrigerator in such manner that it will not interfere with the insertion of a tray in the element nor become frozen to the cooling element when not in use.

A still further object of the invention is to provide a device of this character with the improvement of being capable of movement in a plu-

rality of directions to apply force to pry an ice tray loose from its support.

Specifically my invention takes the form of an ice tray with a projecting portion or reinforcing rim or flange and a device mounted upon but insulated from the cooling element, which device may be manually manipulated in a plurality of directions to engage the projecting portion to the rim, or flange in order to pry the ice tray loose from its support.

Further objects and advantages of the present invention will be apparent from the following description, reference being had to the accompanying drawings, wherein a preferred form of the present invention is clearly shown.

In the drawings:

Fig. 1 is a front view of a mechanical refrigerator having my invention embodied therein;

Fig. 2 is an enlarged view of the tray releasing device of the present invention taken on the line 2—2 of Fig. 1 and showing the device in normal position;

Fig. 3 is a view similar to Fig. 2 and shows the ice tray elevated by the releasing device upon movement thereof in one direction;

Fig. 4 is a view similar to Fig. 2 but shows the ice tray elevated by the releasing device upon movement thereof in a direction opposite that shown in Fig. 3;

Fig. 5 is a sectional view showing the mounting 30 of the tray releasing device on the cooling element and is taken on the line 5—5 of Fig. 2; and

Fig. 6 is a view taken on the line 6—6 of Fig. 2 with a portion of the tray broken away to show association of the tray releasing device with the 35 tray.

Referring to the drawings, for the purpose of illustrating my invention, I have shown a refrigerator cabinet 10 of any conventional and well-known type with the door 11, which affords 40 access to an insulated food storage compartment 12, in open position. A freezing or cooling unit 14 is mounted in the compartment 12 and has a plurality of supports 15 formed thereon or therein for the reception of ice trays 16 adapted 45 to contain a substance to be congealed or frozen by the cooling element. The cooling unit or evaporator may be of any well-known type and is preferably of the sheet metal variety. The freezing or cooling unit 14 is adapted to be connected 50 by suitable pipes or conduits in a closed refrigerating system including a refrigerant liquefying and circulating unit of any conventional design (not shown) but ordinarily housed within a compartment provided in a lower portion of the re- 55

frigerator cabinet 10. A tray releasing device, generally designated by the reference character 20 in Fig. 1, is associated with an ice tray 16 and is preferably secured to or mounted upon the inner side wall of the evaporator or cooling element 14.

The ice tray releasing device 20 associated with the cooling element 14 and with an ice tray 16 includes a mounting block 22 secured by rivets 10 or studs 23 to the inner surface of the double sheet metal walls of the evaporator or cooling unit 14 in any suitable manner, such as by soldering or welding the rivets or studs 23 to the cooling element. (See Figs. 2 and 5.) The 15 mounting block 22 is preferably constructed of a non-metallic material such as micarta, bakelite or the like insulating material for insulating or isolating the tray releasing device 20 from the wall of the cooling element 14 to prevent heat 20 transference therebetween and consequently preventing frosting up or freezing tight of the device. A flat spring 24 has its one end 25 secured to the inner edge of block 22 by a rivet or screw 26. The spring 24 traverses the top of block 22 25 and the opposite end 27 thereof is riveted, by rivets, or otherwise secured to an arm 29 to connect the arm 29 to the block and to normally hold the arm in retracted position out of the way of the ice tray. The arm 29 is constructed, through- 30 out the major portion of its length, of angle iron sheet metal and includes an up-turned portion or finger 31 at its inner end and a bent handle portion 32 at its front end. The portion of the arm 29 intermediate its ends 31 and 32 is normally 35 held in a horizontal position by the spring 24. A finger or upturned member 34 may be formed on the arm 29 at a suitable distance intermediate the mounting block 22 and the handle portion 32 of arm 29. In the present disclosure the finger member 34 is shown as a separate part and secured to the arm 29 by rivets 28 which attach the end 27 of spring 24 to the arm.

The ice trays 16 are of the usual or conventional design and include a rounded-over reinforcing top edge or rim 35 which extends entirely 45 around the trays and at the front forms a handle 36 for facilitating the placing of the trays upon the supports 15 and removal thereof from the evaporator or cooling element 14. Preferably the 50 trays have thin flexible metal walls which will permit warping or flexing of the trays. The trays 16 have side walls which slant or converge outwardly from the bottom to the top of the tray. The trays are preferably provided with rubber 55 grids to enable the ice cubes to be broken loose from the walls of the tray by warping the tray. It will be noted that the spring 24 by holding the arm 29 in its normal or horizontal position maintains the fingers 31 and 34 out of contact with the ice trays 16. The fingers 31 and 34 of arm 60 29 are normally positioned below the downwardly turned edge of rim 35 on the trays 16 to prevent interference of the fingers with the rim 35 during the act of slidably inserting the tray 16 upon its support 15 or during the act of slidably removing a tray from its support.

My improved ice tray releasing device 20 has a double action or, in other words, it may be reciprocated in an upward and/or in a downward 65 direction for prying a tray loose from its support. For example, when it is desired to remove an ice tray 16 from the cooling element 14, which tray has become frozen or bonded to its support 15, the handle end 32 of arm 29 may be operated or 70 removed in a downward direction. The down-

ward movement of the handle end 32 of arm 29 causes the arm to be rocked upon the mounting block 22, or in other words arm 29 is pivoted about the one corner 38 of block 22 as shown in Fig. 4. This rocking of arm 29 about the mounting block 22 causes the inner end of arm 29 to be elevated and, since the fingers 31 and 34 are in vertical alignment with the rim 35 formed on tray 16, the finger 31 will engage the underside of rim 35. Thus force applied to the handle 32 10 will be transmitted by arm 29 and finger 31 to the ice tray 16 to pry the tray loose from its support 15 as illustrated in Fig. 3 of the drawings. When the operator releases handle 32 the arm 29 will be automatically returned to its normal 15 position, as shown in Fig. 2, by the spring 24. The prying action is along one side of the tray 20 near the corner thereof causing the warping or flexing of the tray and is therefore effective for breaking an ice bond between the tray and its 25 support because the flexible tray is substantially peeled away from the support. Thus my improved tray releasing device will pry the tray loose with less force than cam or lever devices which transmit the force to a tray at the longitudinal 30 vertical center thereof or evenly at both sides of the tray. This will also break the ice cubes loose from the walls of the tray by the warping or flexing action.

While I have provided means for insulating or 35 isolating the tray releasing device 20 from the wall of the cooling element 14 to prevent sticking or freezing tight of the device it quite frequently happens that it is desirable or more convenient to elevate or push the handle 32 upwardly instead of downwardly as heretofore described. Therefore my tray releasing device 20 is provided with a double action in order to facilitate operation thereof either in a downward or in an upward direction. When it is desired to remove an 40 ice tray 16 from the cooling element 14, which tray has become bonded or frozen to its support 15, the handle end 32 of arm 29 may be operated or moved in an upward direction. The upward movement of handle end 32 of arm 29 causes the 45 arm to be rocked upon the mounting block 22, or in other words arm 29, is pivoted about the one corner 38 of block 22 as shown in Fig. 3. This rocking movement of arm 29 about the mounting block causes the outward end of arm 29 to be elevated, and since the finger 34 is in vertical alignment with the rim 35 formed on tray 16, the finger 34 will engage the underside of rim 35. Force applied to the handle 32 will be transmitted by 50 arm 29 and finger 34 to the tray 16 to pry the tray loose from its support 15 as illustrated in Fig. 3 of the drawings. The handle 32 upon being released by the operator, preparatory to grasping the tray 16 and slidably removing same from its support 15, will be returned to its normal 55 position shown in Fig. 2 by the spring 24. Obviously therefore my device can be operated in an upward direction to release the tray from its support as well as in a downward direction.

From the foregoing it will become apparent 60 that I have provided an improved device for breaking an ice bond between a tray and its support in a mechanical refrigerator. My improved device in addition to having a double action or in other words, being capable of movement in an upward and/or in a downward direction for releasing a tray from its support, is constructed so as to be isolated from or normally maintained out of contact with the ice tray and insulated from the cooling element whereby the device is ren- 65 70 75

dered operable under varying conditions. The means or spring 24 has the novel double function of normally maintaining the releasing device out of contact with the ice tray and of returning the arm 29 of the device to its normal or horizontal position after the arm has been manipulated or moved into either the upward or downward direction to release a tray.

By mounting the tray releasing device upon a wall of the cooling element independently of the tray, a very firm support is provided for the device. By this arrangement the tray itself may be formed from a thin sheet of metal by a simple stamping operation to provide a flexible tray which may be temporarily warped or deformed to break the ice cubes loose and to remove the tray from its support in the cooling element. By making the tray releasing device double acting, instead of single acting as in prior devices, it is unnecessary to remember in which direction it must be operated and difficulties caused in prior single acting devices by attempted manipulation in the wrong direction and damage resulting therefrom to the device is thus avoided.

While the form of embodiment of the invention as herein disclosed, constitutes a preferred form, it is to be understood that other forms might be adopted, all coming within the scope of the claims which follow.

What is claimed is as follows:

1. A refrigerating apparatus comprising in combination, a cooling element having a support for an ice tray, an ice tray positioned on said support, and means carried by said cooling element and adapted to engage said tray to release the tray from its support, said means being rockably mounted on said cooling element and adapted to be actuated either in a downward or in an upward direction about its mounting to pry the tray loose from its support.

2. A refrigerating apparatus comprising in combination, a cooling member having a support for an ice tray member, an ice tray member positioned on said support, and means movably mounted upon one of said members for applying force to said ice tray member to release same from its support, said means being insulated from both of said members and adapted to be actuated either in a downward or in an upward direction about its mounting to pry the tray member loose from its support.

3. A refrigerating apparatus comprising in combination a cooling element having a support for an ice tray, an ice tray positioned on said support, and means rockably mounted upon said cooling element for applying force to said ice tray to release same from its support, said means being normally out of contact with said ice tray and insulated from said cooling unit and adapted to be actuated either in a downward or in an upward direction about its mounting to pry the tray loose from its support.

4. A refrigerating apparatus comprising in combination, a cooling element having a support for an ice tray, an ice tray positioned on said support, means rockably mounted upon said cooling element for applying force to said tray to release same from its support, said means being adapted to be actuated either in a downward or in an upward direction about its mounting to engage and pry the tray loose from its support, means for in-

sulating said first named means from said cooling element, and means for normally maintaining said first named means out of contact with said ice tray and for returning same to normal position after having been actuated to release the tray.

5. A refrigerating apparatus comprising in combination, a cooling element having a support for an ice tray, an ice tray positioned on said support, a lever rockably mounted upon said cooling element for applying force to said tray to release same from its support, said lever being adapted to be actuated either in a downward or in an upward direction about its mounting to cause engagement of a portion thereof with said tray to pry the tray loose from its support, said lever mounting being constructed of insulating material to isolate the lever from said cooling element, and a spring for normally maintaining said lever out of contact with said ice tray and for returning the lever to normal position after it has been actuated to release the tray.

6. A refrigerating apparatus comprising in combination, a cooling element having a support for an ice tray, an ice tray positioned on said support, means rockably mounted upon said cooling element for applying force to said tray to release same from its support, said means being adapted to be actuated either in a downward or in an upward direction about its mounting to pry the tray loose from its support, and means for normally maintaining said first named means out of contact with said ice tray and for returning same to normal position after having been actuated to release the tray.

7. A refrigerating apparatus comprising in combination, a cooling element having a support for an ice tray, an ice tray positioned on said support, and means associated with said ice tray and said cooling element for applying force to said tray at a point remote from the longitudinal vertical center thereof to release the tray from its support, said means being rockably mounted and adapted to be actuated either in a downward or in an upward direction about its mounting to substantially peel the tray loose from its support.

8. A refrigerating apparatus comprising in combination, a cooling element having a support for an ice tray, an ice tray positioned on said support, and a lever associated with said ice tray and said cooling element for applying force to said tray at a point remote from the longitudinal vertical center thereof to release the tray from its support, said lever being rockably mounted and adapted to be actuated either in a downward or in an upward direction about its mounting to substantially peel the tray loose from its support.

9. A refrigerating apparatus comprising in combination, a cooling element having a support for an ice tray, an ice tray positioned on said support, and means carried by the cooling element in position to engage said tray at a point remote from the longitudinal vertical center thereof to apply force to release the tray from its support, said means being mounted to be actuated in either of two opposite directions to substantially peel the tray loose from its support on movement in either of said two directions.

CARL A. STICKEL.
